WIRELESS TELEPHONY.

970,850.

Specification of Letters Patent. Patented Sept. 20, 1910.

Application filed February 12, 1908. Serial No. 415,536.

To all whom it may concern:

Be it known that I, ALBERT PLISNIER, Jr., subject of the Emperor of Austria-Hungary, residing at Stuttgart, in Würtemberg, Germany, have invented certain new and useful Improvements Relating to Wireless Telephony, of which the following is a specification.

This invention relates to wireless telephony by means of undamped electric waves, and particularly to a switching arrangement therefor.

As is well known, to render wireless telephony possible by means of undamped waves, a microphone is switched in shunt 15 to an inductance in the "Duddel" oscillating circuit. In this kind of switching, however, the electric-acoustic action upon the oscillating circuit is very small so that the corresponding curve of oscillation attains 20 only very small amplitudes with the result that the waves sent are influenced very weakly by speech. Further, the life of a microphone in a strong current by direct switching to the poles of the self-induction 25 coil where the greatest tension prevails is very short, or very high tension currents pass through the microphone, so that the latter becomes useless in view of the great heat developed and finally burns out. The present invention overcomes these disadvantages 30 and embodies a circuit in shunt consisting of a microphone and capacity switched to the poles of a self-induction coil of the oscillating circuit and connected with the 35 earth in the center between the microphone and capacity. By this means very great fluctuations of current are produced even if the operator in speaking uses a soft voice or tones, and the heating of the microphone 40 is avoided, so that it is always operative and its life is therefore prolonged.

The advantages obtained by the present invention may be explained by occurrences as follows: First: by switching a regulable 45 condenser into the microphone circuit an operator is enabled to diminish the tension upon the microphone as desired or to change the same in any manner. Second: the two points to which the microphone and the condenser circuit are connected on the coil must be considered as the poles furnishing the tension, or source of supply, for this circuit 50 across the microphone and condenser. The

ohmic resistance w of the microphone is made equal to reactance w^2 of capacity of 55 the condenser so that w , equals w^2 , consequently i intensity at the microphone would also be equal to i^2 intensity at the condenser and very slight changes of w , as trials have shown, produce very great fluctuations in 60 the microphone and condenser circuit.

The Duddel oscillating circuit may be fed by any kind of exciter of current waves, for instance, by a mercury vapor lamp spark gap with a coöperating high tension alternating current, or by an electric arc fed by a high tension direct current.

In the accompanying drawings:—Figure 1 illustrates a diagrammatic view of an organization for producing undamped electrical waves and embodying the features of 70 the invention. Fig. 2 is a similar view showing a different arrangement.

Referring to Fig. 1, the aerial is directly and electrically excited and the reference 75 character a designates an alternating current supply; b a high tension transformer; c a mercury vapor lamp spark gap, and the oscillating circuit consists of a condenser e and a self-induction coil f . With the poles 80 of the coil f , the circuit in shunt consists of a microphone i and rotary condenser k which are connected to the said coil poles. The aerial is designated by g , and h is the 85 earth or an electrical counterweight connection which is made, as shown, in the center between the microphone and capacity.

In Fig. 2 the aerial is inductively, or magnetically, excited, the direct current being furnished by a high tension storage battery 90 a' and passes through the choking coils b' and feeds the electric arc c' which excites the oscillating circuit consisting of capacity e' and self-induction coil f' . To this Duddel circuit a second coil f'' is inductively and 95 loosely coupled, and to this second coil the aerial g' and earth or counterweight h' are connected. The arrangement or switching of the microphone i' and the rotary condenser k' is the same as shown by Fig. 1. 100

What is claimed is:

A switching organization for wireless telephony by means of undamped electric waves, consisting of an oscillating circuit embodying a self-induction coil, and a shunt 105 circuit embodying a microphone and ca-

5 pacity switched to the poles of the self-induction coil and earthed at a point between the said microphone and capacity, whereby the tension on the microphone may be changed or diminished at will and the electric-acoustic action of the oscillating circuit may be increased.

In testimony whereof I have hereunto set my hand in presence of two subscribing witnesses.

ALBERT PLISNIER, JUN.
